UNITED STATES PATENT OFFICE

2,556,056

CIRCUIT BREAKER

Alfred Bally, Bassersdorf, Switzerland, assignor
to Maschinenfabrik Oerlikon, Zurich-Oerlikon,
Switzerland, a Swiss firm

Application October 15, 1945, Serial No. 622,369

7 Claims. (Cl. 200—150)

1

This invention relates to circuit breakers and more especially to power circuit breakers of low liquid content.

To this end, in accordance with the present invention, in a low liquid content power circuit breaker of the wall-mounting type, two insulating tubes which are disposed in V shape, communicate at the bottom, and are filled with the quenching liquid; of these, the first insulating tube is supported at its upper end on the base of the circuit breaker, while the second insulating tube contains a circuit-breaking chamber and is provided at its two ends with the circuit breaker poles, while, however, the movable contact, in breaking the circuit, moves from top to bottom and is moved by a mechanism disposed in the lower circuit breaker pole by means of an insulating rod, which is guided inside the first insulating tube upwards to the actuating device located in the base.

The result of this design is that the mechanism required for opening the movable circuit breaker contact, and also the actuating rod leading to the base, are completely unexposed to the influence of weather, and thus the safety in operation of the circuit breaker is further improved. However, greater circuit-breaking power is also obtained, because the movable contact, on the circuit being broken, is always drawn into fresh oil and the gas bubbles escape in the opposite direction, i. e. upwards. In addition, circuit breakers in accordance with the present invention, can easily be converted into change-over switches. Further development of these circuit breakers moreover, permits the employment of additional supporting insulators in circuit breakers of greater power, while these supporting insulators can contain current transformers which are combined with the insulators. Particular advantages, especially for circuit breakers which are accommodated in circuit breaker cells, are thereby obtained.

In order to enable the invention to be more readily understood reference is made to the accompanying drawings which illustrate diagrammatically and by way of example, various embodiments thereof, and in which:

Fig. 1 shows the fundamental construction of a circuit breaker according to the present invention, and also the employment of an additional insulating tube inserted between the upper switch pole and the base.

Fig. 2 shows a circuit breaker according to Fig. 1, in which the lower switch pole is supported against the base by a solid and preferably hori-

2

zontally guided supporting insulator. This supporting insulator can be designed as a lead-in bushing.

Fig. 3 shows a top view of three circuit breakers according to Fig. 2 secured side by side on a common base.

Fig. 4 indicates the further development of a circuit breaker according to Fig. 1 or Fig. 2 to form a change-over switch in which the change-over contact is likewise operated by actuating mechanisms and rods immersed in oil.

Fig. 5 shows a circuit breaker according to Fig. 1, having a vertically disposed supporting insulator, and mounted on a special travelling stand.

Fig. 6 shows a modification of Fig. 5, in which the vertical supporting insulator is designed as a lead-in bushing for a lead issuing through the base of the circuit-breaker source.

Fig. 7 shows a circuit breaker according to Fig. 5, which is combined with a driving stand containing the entire actuating mechanism.

In the embodiment illustrated in Fig. 1, the two insulating tubes 3, 10 are disposed in V fashion and tube 10 has one of its ends secured to a base 8. The other insulating tube 3 carries at its two ends the switch poles 3a and 3b provided with the connections. The fixed contact 4 is connected to the upper switch pole 3a, and the movable contact 5 to the lower switch pole 3b, by way of guide members 7. Inside the tube 3 is located the circuit-breaking space 4, in which the arc is drawn. The actual circuit-breaking chamber is omitted for the sake of clarity. In the metallic casing forming the lower switch pole is mounted a double lever, which is moved by the insulating rod 6, adapted to move axially in the hollow space of the tube 10, and which is coupled to the contact 5.

The base 8 of the circuit breaker is preferably designed, at least partially, as a reservoir for the arc quenching liquid, the reservoir space communicating directly with the hollow space in the support 10. The actuating rod 6, disposed

inside the tube 10, is provided with an extension 11 which penetrates the reservoir at a point above the level of the liquid, so that only simple stuffing boxes are required for sealing. The actuating device comprising a lever 9 is mounted outside the reservoir. It is occasionally advantageous to provide still a further insulating tube 2 between the upper switch pole and the base 8. This insulating tube 2 connects the reservoir located in the base 8 with the space in the upper pole of the circuit breaker.

The circuit breaker illustrated in section in Fig. 2, consists of the two insulating tubes 3, 10, which are disposed in V fashion, intercommunicating at the bottom, and are filled with the quenching liquid, such as oil. The insulating tube 10 is provided at its upper end with a metal cap 20 and is supported on the base 8, which can consist of a U-girder. The other insulating tube 3 contains the circuit-breaking chamber 15 and is equipped at its two ends with the switch poles 16, 17, the fixed switch contact 4 being electrically connected with the upper pole 17 of the circuit breaker, and the movable switch contact 5 with the lower pole 16. The movable contact 5 is accordingly moved, during the breaking of the circuit, from top to bottom. In the casing of the lower pole 16 of the circuit breaker is also provided an actuating mechanism consisting of the angle lever 14 and the connecting plate 18. This driving mechanism is operated by the insulating rod 6, which leads upwards in the insulating tube 10 and is pivoted to the metal rod 12. The metal rod 12 penetrates the cap 20 in a stuffing box lying above the level of the liquid. The actuating device is secured on the base 8 and consists of the lever 9 and the connecting plate 19.

The circuit breaker illustrated in Fig. 2 is particularly designed as a circuit breaker of the wall-mounting type, and the base 8 is secured directly to the usually perpendicular wall. The lower pole 16 of the circuit breaker is supported against the wall by means of an additional supporting insulator 21 lying beneath the insulating tube 10. Use is advantageously made of the design illustrated, in which the base 8 of the circuit breaker is lengthened vertically to such an extent that the supporting insulator 21 rests on its lower portion and the insulating tube 10 on its middle portion, while the actuating device 9, 19 is disposed on its upper portion. In contradistinction to a design in which the whole circuit breaker is secured on the wall only by the cap 20 designed as the base, a mechanically substantially more dependable and also more inexpensive design of circuit breaker is thus obtained. A further advantage, moreover, consists in the fact that the additional supporting insulator 21 can be designed as a lead-in insulator for the lead issuing from the lower pole 16 of the circuit breaker. The supporting insulator conveniently penetrates the base 8 and the wall lying therebehind, and is supported on the base 8 by means of a flange. It is particularly convenient to design the lead-in insulator 21 at the same time as a current transformer, and to secure the secondary terminals of the current transformer, to which the load is connected, on the base 8.

The afore-described circuit breaker is, above all, suitable for the construction of polyphase circuit breaker arrangements, as is indicated in Fig. 3. A plurality of single-phase units according to Fig. 2 are disposed side by side with the desired phase distance, the base 8 of the single-phase units being joined together at top and bottom by cross members 22. A continuous shaft 23 ensures the simultaneous operation of all three circuit breakers.

In order to employ a normal on-off circuit breaker as a change-over switch, it would at first sight appear obvious to provide two separate circuit breakers and to operate or control them in such a manner that when one of the circuit breakers is opened, the other is auto-

matically closed. This can always be put into practice by suitably coupling the operating mechanisms. The special design of the circuit breakers of the present invention, however, permits also a substantially simpler and cheaper solution, without coupling together two circuit breakers, as has hitherto been customary. On the contrary, a single circuit breaker of the type illustrated in Figs. 1 and 2 is sufficient; a circuit breaker of this type can be converted into a change-over switch by means of an additional part. Not only is the manufacture of a change-over circuit breaker simplified thereby, but a considerable saving in space is also achieved. Such a circuit breaker is illustrated in section in Fig. 4. The two insulating tubes 3, 10, which intercommunicate at the bottom, are disposed in a V arrangement and filled with quenching liquid. The insulating tube 10 is provided at its upper end with a metal cap 26 and is supported on the base 8, which can consist of a U-girder secured to the wall. The other insulating tube 3 contains a circuit-breaking chamber 15, and is provided at its two ends with the switch poles 16, 17, the fixed contact 4 being electrically connected to the upper circuit breaker pole 17 and the movable contact 5, by way of the guides 27 designed as current offtake pieces, to the lower switch pole 16. The casing forming the lower pole 16 of the circuit breaker also accommodates an actuating mechanism consisting of the angle lever 14 and the connecting plate 18 for driving the movable contact 5. Said actuating mechanism is moved by the insulating rod 6, which leads upwards in the insulating tube 10 and is pivoted to the metal rod 12. The control rod 12 penetrates the cap 20 in a stuffing box lying above the level of the liquid and is moved in its axial direction by the actuating device consisting of the lever 9 and the coupling plate 19. The actuating device is disposed on the base 8.

Fig. 4 illustrates a circuit breaker of the wall-mounting type, in which preferably the lower pole 16 of the circuit breaker is supported against the wall by means of an additional supporting insulator 21 disposed below the insulating tube 10. The supporting insulator 21 can be designed as a lead-in insulator for the lead issuing from the pole 16 of the circuit breaker, penetrating the wall and being supported on the base 8 by means of a flange.

Instead of the cover closing the bottom of the casing 16, a third insulating tube 28 is disposed on the pole of the circuit breaker provided with the mechanism 14, 18, and extends in the opposite direction to the insulating tube 3. Said third insulating tube 28 contains a circuit-breaking chamber 25, a fixed switch contact 24 electrically connected to the third pole 25, and a movable contact 29 electrically connected to the pole 16. The movable switch contact 29 and the movable contact 5 are jointly moved by the mechanism 14, 18, in such a manner that in the two end positions one of the two pairs of switch contacts is always open and the other closed. The two movable switch contacts 29, 5 are moved by the insulating rod 6, so that with simple means a change-over switch is produced which, as can be seen, can be obtained by simply adding the insulating tube 28 having a fixed switch contact 24 and the movable switch contact 29 to a normal circuit breaker.

Figs. 5 to 7 show circuit breakers according to the present invention, in which an additional supporting insulator is provided, which is dis-

posed at least approximately in the axial direction of the insulating tube containing the circuit-breaking chamber, and which supports the circuit breaker against the ground. In all these figures the two insulating tubes disposed to form a V with one another are designated by 3 and 10. The second insulating tube 3 contains at its two ends the poles 16, 17 of the circuit breaker. The movable contact is moved from bottom to top in the insulating tube 3 when the circuit is broken. The driving mechanism which drives the movable contact is disposed in the lower pole 16 of the circuit breaker. The driving mechanism is in turn operated by an insulating rod which is guided upwards in the first insulating tube 10. The first insulating tube ends at the top in a metal cap 20, through which passes, in the embodiments illustrated in Figs. 1 and 2, an axially slideable and packed rod 12, which is coupled to the insulating rod for the purpose of operating the driving mechanism. The lower pole 16 of the circuit breaker is supported against the ground by means of the additional supporting insulator 34 in the axial direction of the second insulating tube 3.

In Figs. 5 and 7 the additional supporting insulator 34 is mounted on a traveling stand 32, while in Fig. 6 the additional supporting insulator 35 is designed as a lead-in insulator. All figures have in common the fact that the first insulating tube 10 likewise receives further support at its upper end by means of the metal cap 20. In Fig. 1 and 2 this support is on the wall base 8 provided with the actuating device 9, 19 while in Fig. 7 the support is on the actuating pillar 30, which is mounted together with the circuit breaker on the common ground base 8.

The actuating pillar 30 can be covered by a casing, and in addition to the actuating device may contain the actual drive, for example a manual drive, electric motor or pneumatic drive, or else a power storage drive. In addition, it is convenient also to accommodate in the pillar the operating relays and their accessories. Particular advantages are afforded by a circuit breaker design according to Fig. 6, in which the circuit breaker is disposed in a circuit breaker cell, and in consequence a lead-in insulator, in the form of a ground lead-in, can also be used as supporting insulator 35. At the same time the lead-in insulator can be designed as a current transformer.

What I wish to secure by United States Letters Patent is:

1. In an electric circuit breaker of the character described, two insulating tubes having their lower ends connected adjacent each other to a metallic casing to form with the latter a V-shaped container filled with an arc-quenching liquid, one of said insulating tubes being arranged vertically and forming a switch chamber for a fixed contact and a movable contact adapted to engage and disengage said fixed contact, both said contacts being continuously immersed in said liquid, a base adapted to be attached to a wall and having attached thereto the upper end of the other insulating tube which is arranged at an acute angle with respect to the vertically positioned tube, a switch pole closing the upper end of the vertical insulating tube and carrying said fixed contact which extends downwardly into said tube, said movable contact being conductively connected with said metallic casing and extending upwardly into said tube, lever means pivotally mounted in said casing and

operatively connected with said movable contact in a manner causing an axial movement of the same within its insulating tube upon pivotal movement of said lever means, switch operating means mounted on said base adjacent the upper end thereof, and means including an axially movable insulating rod extending axially through the tube attached with its upper end to said base above the surface of said liquid and operatively connecting said switch operating means with said lever means in said casing for actuating said movable contact.

2. In an electric circuit breaker of the character described, two insulating tubes having their lower ends connected adjacent each other to a metallic casing to form with the latter a V-shaped container filled with an arc-quenching liquid, a base adapted to be attached to a wall, means for closing the upper end of one of said insulating tubes and for attaching it to said base, a switch pole closing the upper end of the other insulating tube, a fixed contact carried by said switch pole and extending into said tube, an axially movable contact rod conductively connected with said metallic casing extending from the latter upwardly into said last mentioned tube, both said contacts being continuously immersed in said liquid, lever means pivotally mounted in said casing and operatively connected with said contact rod in a manner to move the same in its axial direction selectively into and out of engagement with said fixed contact upon pivotal movement of said lever means, switch operating means mounted on said base, and means including an axially movable insulating rod extending axially into the upper end of and through the tube attached with its upper end to said base and operatively connecting said switch operating means with said lever means in said casing for actuating said movable contact rod, the exit of said operating means being above the surface of the liquid.

3. In an electric circuit breaker as claimed in claim 2, a third insulating tube attached to the bottom of said metallic casing in axial alignment with said vertically positioned tube and in open communication with the interior of said casing, and a second fixed contact in said third insulating tube, all said contacts being continuously immersed in said liquid, said movable contact rod being adapted to be moved selectively into engagement with either one of said two fixed contacts.

4. In an electric circuit breaker of the character described, two insulating tubes having their lower ends connected adjacent each other to a metallic casing to form with the latter a V-shaped container filled with an arc-quenching liquid, one of said insulating tubes being arranged vertically and forming a switch chamber for a fixed contact and a movable contact adapted to engage and disengage said fixed contact, both said contacts being continuously immersed in said liquid, a base adapted to be attached to a wall and having attached thereto the upper end of the other insulating tube which is arranged at an acute angle with respect to the vertically positioned tube, a supporting insulator connecting the metallic casing with said base, a switch pole closing the upper end of the vertical insulating tube and carrying said fixed contact which extends downwardly into said tube, said movable contact being conductively connected with said metallic casing and extending upwardly into said tube, lever means pivotally mounted

in said casing and operatively connected with said movable contact in a manner causing an axial movement of the same within its insulating tube upon pivotal movement of said lever means, switch operating means mounted on the upper end of said base, and means including an axially movable insulating rod extending axially through the tube attached with its upper end to said base and operatively connecting said switch operating means with said lever means in said casing for actuating said movable contact, the exit of said operating means being above the surface of said liquid.

5. In an electric circuit breaker of the character described, two insulating tubes having their lower ends connected adjacent each other to a metallic casing to form with the latter a V-shaped container filled with an arc-quenching liquid, one of said insulating tubes being arranged vertically and forming a switch chamber for a fixed contact and a movable contact adapted to engage and disengage said fixed contact, both said contacts being continuously immersed in said liquid, a base adapted to be attached to a wall and having attached thereto the upper end of the other insulating tube which is arranged at an acute angle with respect to the vertically positioned tube, an insulator attached to the bottom of the metallic casing in substantial axial alignment with said vertically arranged insulating tube and adapted to support the circuit breaker from the floor, a switch pole closing the upper end of the vertical insulating tube and carrying said fixed contact which extends downwardly into said tube, said movable contact being conductively connected with said metallic casing and extending upwardly into said tube, lever means pivotally mounted in said casing and operatively connected with said movable contact in a manner causing an axial movement of the same within its insulating tube upon pivotal movement of said lever means, switch operating means mounted on the upper end of said base, and means including an axially movable insulating rod extending axially through the tube attached with its upper end to said base and operatively connecting said switch operating means with said lever means in said casing for actuating said movable contact, the exit of said operating means being above the surface of said liquid.

6. In an electric circuit breaker of the character described, two insulating tubes having their lower ends connected adjacent each other to a metallic casing to form with the latter a V-shaped container filled with an arc-quenching liquid, one of said insulating tubes being arranged vertically and forming a switch chamber for a fixed contact and a movable contact adapted to engage and disengage said fixed contact, both said contacts being continuously immersed in said liquid, a base adapted to be attached to a wall and having attached thereto the upper end of the other insulating tube which is arranged at an acute angle with respect to the vertically positioned tube, an insulator mounted on a travelling stand attached to said metallic casing substantially in axial alignment with said vertically arranged insulating tube for supporting the circuit breaker from the floor, a switch pole closing the upper end of the vertical insulating tube and carrying said fixed contact which ex-

tends downwardly into said tube, said movable contact being conductively connected with said metallic casing and extending upwardly into said tube, lever means pivotally mounted in said casing and operatively connected with said movable contact in a manner causing an axial movement of the same within its insulating tube upon pivotal movement of said lever means, switch operating means mounted on the upper end of said base, and means including an axially movable insulating rod extending axially through the tube attached with its upper end to said base, said insulating rod operatively connecting said switch operating means with said lever means in said casing for actuating said movable contact, the exit of said operating means being above the surface of said liquid.

7. In an electric circuit breaker of the character described, two insulating tubes having their lower ends connected adjacent each other to a metallic casing to form with the latter a V-shaped container filled with an arc-quenching liquid, one of said insulating tubes being arranged vertically and forming a switch chamber for a fixed contact and a movable contact adapted to engage and disengage said fixed contact, both said contacts being continuously immersed in said liquid, a base adapted to be attached to a wall and having attached thereto the upper end of the other insulating tube which is arranged at an acute angle with respect to the vertically positioned tube, an insulator attached to the bottom of the metallic casing in substantial axial alignment with said vertically arranged insulating tube and adapted to support the circuit breaker from the floor, said insulator forming a bushing for a lead-in conductor which is connected to said metallic casing, a switch pole closing the upper end of the vertical insulating tube and carrying said fixed contact which extends downwardly into said tube, said movable contact being conductively connected with said metallic casing and extending upwardly into said tube, lever means pivotally mounted in said casing and operatively connected with said movable contact in a manner causing an axial movement of the same within its insulating tube upon pivotal movement of said lever means, switch operating means mounted on the upper end of said base, and means including an axially movable insulating rod extending axially through the tube attached with its upper end to said base and operatively connecting said switch operating means with said lever means in said casing for actuating said movable contact, the exit of said operating means being above the surface of said liquid.
